J. SCHACHT.

DANGER SIGNAL FOR AUTOMOBILES.

APPLICATION FILED JAN. 14, 1919.

1,336,381.

Patented Apr. 6, 1920.

UNITED STATES PATENT OFFICE.

JULIUS SCHACHT, OF NEW YORK, N. Y.

DANGER-SIGNAL FOR AUTOMOBILES.

1,336,381.

Specification of Letters Patent.

Patented Apr. 6, 1920.

Application filed January 14, 1919. Serial No. 271,132.

To all whom it may concern:

Be it known that I, JULIUS SCHACHT, a citizen of the United States, and a resident of the city of New York, borough of Manhattan, in the county and State of New York, have invented a new and Improved Danger-Signal for Automobiles, of which the following is a full, clear, and exact description.

- 10 This invention relates to safety signal devices for use by automobile drivers or the like, and has particular reference to the means of a practical and reliable nature to relieve the driver from the customary and unsatisfactory practice of projecting a hand laterally outward beyond the vehicle for the purpose of indicating to an on-coming driver or other persons the fact that a stop, turn, or the like, is about to be made.
- 15 Another object of the invention is to provide a signal that may be readily seen by persons either in front of or behind the vehicle carrying the signal, and which may be projected either by hand or foot means, and
- 20 which furthermore may be locked in projected position so as to relieve the operator of the vehicle from constant manual control, leaving his hands free for the control of the steering or driving mechanism of the
- 25 machine, but means obviously will be provided for the release of the holding means so that the signal will return automatically to normal secluded position.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings, in which like reference characters designate the same parts in the several views, and in which—

45 Figure 1 is an elevation showing my improvement in operation.

Fig. 2 is a vertical transverse section on the line 2—2 of Fig. 1.

50 Fig. 3 is a detail view in elevation indicating the catch means to hold the device in projected position.

Fig. 4 is a section on the line 4—4 of Fig. 1.

Fig. 5 is a front elevation of the device housed in its casing; and

Fig. 6 is a diagram indicating the pedal connections with the two signal devices on opposite sides of the machine.

Referring now more specifically to the drawings I show my invention as comprising a casing or housing 10 fixed in any suitable stationary support, as for example, on the dashboard or the wind shield frame of an automobile, such support being represented at 11. The casing may be supported either at the right or left side of the vehicle according to the side on which the driver is seated, or if desired the device may be duplicated and have connections between the devices on opposite sides of the vehicle so that the signal may be displayed simultaneously at both sides of the vehicle, especially in connection with the foot operated means for controlling it. This is a matter of considerable importance in view of the desirability for the driver seated for example on the left side of the vehicle to project his hand or other signaling means to the right of the vehicle to indicate a proposed right turn. It is well understood that the expedient of projecting one's hand from the side of the vehicle opposite from where he is sitting is an awkward one, and sometimes practically impossible.

In the conception and design of this device I have had in mind the expedient of displaying a signal element as large and as conspicuous as the conditions will warrant and yet which will occupy a minimum amount of space when idle, and whereby consequently the device in its idle position is inconspicuous and practically unnoticeable. In carrying out my invention, therefore, in a practical embodiment I anchor within the casing 10 a series of lazy tong devices, the first bar 12 of which is fixed adjacent to the inner edge portion 10^a of the casing in vertical position. Another bar 13 pivoted at its center at 14 to the first bar 12 constitutes the actuating lever and is projectable through a slot 15 formed in the wall 10^a of the casing. In its normal position the lever 14 lies practically parallel to the bar 12, but when operated the upper end of the lever 14 which carries a finger piece 16, or its equivalent, is movable inward and downward through

an arc of about 90° bringing the bar 14 to horizontal position. All of the remaining bars 17 of the lazy tongs are pivoted to one another in the usual manner of lazy tongs, and hence when the lever 14 is swung inward and downward as described to horizontal position the remote end of the system of levers is swung outward and upward through a curved arc and to a distance well beyond the outer open side of the casing.

The upper and lower ends of the outermost pair of links or bars 17' carry a rigid link-like member comprising parallel bars 18 and 19, the former of which is fixed at 15 its lower end to a foot piece 20 fixed rigidly to the lower end of the one bar 17' and having a slidable connection through an eye 21 with the other bar 17'. The bar 19 of the link is thus held spaced rearward from the 20 plane of the lazy tong bars and has fixed permanently to it the outer end of a flexible strip of signal material such as a red banner, or its equivalent 22. The signal member is 25 rolled at its other end upon a spring operated roller 23 journaled in a bracket 24 having a relation to an upper and lower pair of toggle joints intermediate the ends of the system of toggle bars similar to the relation of the bars 18 and 19 to the outermost ends 30 of the lazy tongs. More definitely the bracket 24 includes a bar 24^a having its lower end fixed in a foot piece 25 while the upper portion of the bar 24^a has slidable connection in a guide 26 fixed to the joint directly above 35 the foot piece 25. The roller 23 is journaled in the rearward extensions of the bar and foot piece and is spring operated whereby the signal member will automatically roll thereon when the lazy tongs are collapsed.

40 When the lever 14 is swung inward and downward at its lower end as described the signal member is projected quickly and reliably outward and upward from the open sided casing and because the first bar of the 45 lazy tongs is anchored in a vertical position and the lower end of the actuating lever 14 is thereby swung outward and upward through about 90° it follows that the outer end of the lazy tongs, carrying the signal 50 member, is moved upward as well as outward so that it has a tendency to return by gravity automatically to its normal secluded position when the lever 14 is released. It follows, therefore, that there is no tendency 55 for the signal member to swing or otherwise move inadvertently from its hidden position.

For most purposes the lever 14 may be 60 actuated entirely by hand either for the projection of the signal member or for holding it in display position. If, however, it is desirable to relieve the operator from using his hand after projecting the signal member an automatic spring catch of any suitable nature indicated at 27 may be employed to snap 65 over the upper edge of the lever 14 for

holding it down. This spring is indicated as anchored at its lower end and having a finger piece or loop 28 at its upper end which may be engaged over a pin or stud 29, if desired, to uphold it in idle position so that if 70 the catch is not desired by any particular individual it will not operate to engage and hold the lever. Usually, however, the driver has need for both of his hands especially at the time when a turn is being made so it is 75 usually desirable to employ the catch to engage and hold the lever automatically. To release the lever the operator has but to draw rearward upon the loop 28 to set free the lever 14 when the signal member will gravitate promptly to its nested position.

Any suitable foot mechanism such as a 80 pedal 30 may be provided to actuate the signal means. A flexible connection 31 of any suitable nature may be attached to either or 85 both of the levers 24 to actuate them inward and downward. The pedal 30 may be connected to both of these devices, and when located midway between the two sides of the dashboard may operate both of them simultaneously, but the connections may be so arranged that by moving the pedal to the left for example the left signal connection will be slackened so that the actuation of the 90 pedal will project only the signal device at 95 the remote side of the vehicle. Consequently the driver may depend upon the foot actuation only for the remote signal while he may control the closer and more convenient signal by his hand.

I claim:

1. In a signal device for automobiles, the combination of a relatively fixed casing, a flexible display member carried normally in rolled form within the casing and means to 105 project the display member from the casing, said projecting means comprising a plurality of lazy tongs, and connections between the opposite ends of the display member and the lazy tongs whereby when the lazy tongs are projected the display member will be 110 extended, said display member being carried entirely by the lazy tongs.

2. In a signal device for automobiles, the combination of a relatively fixed casing, lazy 115 tongs devices anchored in the casing and carried normally in folded position therein, a link member carried by the outermost ends of the lazy tongs and comprising two parallel bars, another bar member carried by the 120 intermediate joints of the lazy tongs and parallel to the link member, a spring operated roller journaled in the latter mentioned bar member, and a flexible display member secured at one end to the roller and secured at its other end to the link member whereby when the lazy tongs are projected the display member will be automatically 125 unrolled from the roller and projected upward into display position.

3. In a safety signal, the combination of a rigid support, a series of lever members pivoted to one another, the first lever constituting the actuator and pivoted on a fixed 10
5 pivot to said support intermediate the ends of the lever, a flexible signal member carried normally in rolled form adjacent to the support, and means carried by the lever members serving to cause the signal member to be unrolled into flat display position and at the same time to be swung outward and upward by the actuation of the actuating lever providing thereby for the automatic return by gravity of the signal member when the actuator is released.

JULIUS SCHACHT.
